STARTING AND OPERATING CIRCUITS FOR FLUORESCENT LAMPS

William S. H. Hamilton, Larchmont, N. Y.

Application June 30, 1950, Serial No. 171,495

4 Claims. (Cl. 315—103)

This invention relates to improvements in starting and operating circuits for fluorescent lamps, and particularly to fluorescent lamps of the types which are difficult to start and which require an inductive kick to start them into operation when they are sufficiently preheated to fire.

The object of the invention is to provide circuit arrangements embodying novel starting and controlling means adapted to give an effective inductive kick to start the lamp when it is otherwise ready to fire, and which overcomes functional defects of some of the starters in general use in the way of ensuring greater reliability in action and a more readily and rapid starting of the lamp, without repeated starter actions, if the lamp is in good order and free from mechanical or electrical defects.

In the accompanying drawings I have shown in Figs. 1 to 4 inclusive, diagrammatic views of circuit arrangements for D. C. and A. C. lamps embodying my invention, which are adapted to give an effective inductive kick for a starting action, all of which also show a glow in one or more filaments as soon as the circuit is closed, and all of which also designed to quickly restart after they have been in use and it is desired to restart them without the usual restarting delays.

Figs. 5 and 6 are views showing a snap action type of starter which may be desiredly used in the circuits, the views showing the closed and open positions of a normally closed starter and corresponding positions of a coacting relay switch.

Referring now more particularly to Fig. 1 of the drawings, 1 designates a gas containing fluorescent lamp envelope having spaced negative and positive electrodes 2 and 3, the electrode 2 being of filamentary type while the electrode 3 is short-circuited. One end of the negative electrode 2 is connected by a lead conductor 4 to the negative terminal 5 of a D. C. line, while the other end of said electrode is connected to a conductor 6 forming part of a primary preheating circuit and having arranged therein current limiting resistances 7 and 8, the heating resistance 9 of a thermostatic starter 10, and the automatically closing switch member 11 of a starting and operating relay 12. One end of the electrode 3 is connected through an operating conductor, having input and output portions or branches 13' and 13'', to the positive terminal 14 of the line. The said portions 13', 13'' are connected at a common junction point to the input conductor 15' of a normally open secondary preheating and control circuit. Such circuit includes the conductors 13' and 15' and an output conductor 16', connected at its output end to the conductor 6 between the resistances 7 and 8.

The proximate ends of the conductors 15' and 16' are separated by a gap adapted to be bridged by engagement of the contacts 17 and 18 of the normally open thermostatic starter 10. A condenser 19 is placed across the contacts 17—18 to prevent arcing when said contacts open. The relay 12 includes a by-pass connection 20 disposed between the input ends of the conductors 6 and 13', which is normally closed by the switch 11, and a relay coil 21.

A condenser 12' is placed across the contacts of switch 11 to prevent arcing when said contacts open.

The coil 21 is disposed in the conductor 13' between the reactor 23 and the conductor branch 13'', so as to be cut out of the path of flow of preheating current in the primary preheating circuit, and arranged to be normally de-energized when the switch member 11 is closed. Also, coil 21 is so arranged as to be energized when the lamp fires under line voltage, or when the thermostatic switch contacts 17—18 close to retract the switch 11, which breaks the preheating circuit 6. A reactor coil 23 is arranged in the conductor branch 13' ahead of the relay coil and operates to give an inductive kick to start the lamp when the contacts 17—18 open after having been closed, if the lamp, after being heated, does not fire directly under line voltage applied to the filament 3 through the conductor 13'. A ballast lamp 22 of proper current limiting value is arranged in the conductor 13''.

In starting, current flows from the line through connection 26, the normally closed self-closing relay switch 11, and through the heater 9 and resistances 7 and 8 in conductor 6 to the filament 2 and back to the line, thus heating the filament 2. If the lamp then does not start on line voltage before the thermostatic switch contacts 17—18 close, on the closing of these contacts the relay will pick up and open the switch 11 and the secondary preheating circuit will be established from the line through conductors 13', 13'', 16' and resistance 8 to continue the preheating of the filament 2.

When the contacts 17—18 of the thermostatic switch open, an inductive kick will be generated by opening the circuit through the reactor coil 23 sufficient to fire the lamp. When the lamp fires the relay coil 21 will be energized through conductors 13' and 13'' and ballast lamp 22, opening the primary preheating circuit of conductor 6 and preventing further action on the part of thermostatic switch 10. This circuit arrangement permits starting of a hard starting lamp without preheating the electrode 3 and gives satisfactory results with certain types of lamps of this character.

Fig. 2 shows a circuit arrangement which is suitable for use with either an A. C. or D. C. source of current supply and which is similar to that of Fig. 1 except that electrode 3 is of filamentary type and connected in series with the operating conductor sections 13', 13'' containing the relay coil 21, ballast lamp 22 and reactor 23 and with the conductor 15 leading to the thermostatic switch device 10. The operation of this circuit arrangement will be readily understood in the light of the foregoing description applying to the operation of the circuit arrangement shown in Fig. 1.

Fig. 3 shows a circuit arrangement in which a preheating and operating conductor 13c leading from terminal 14 is normally connected by a self-closing relay switch 11c arranged therein with a preheating conductor section 6d which is normally connected by the normally closed contacts 17—18 of the thermostatic switch 10' with a conductor 6e containing the heater element 9 and current limiting resistance 8b and leading to the negative filament 2 of the lamp 1.

The relay coil 21b is arranged between a conductor 20b and an operating conductor section 13d leading to the positive filament 3 of the lamp, which is short-circuited. In the lead 13c between the terminal 14 and the switch 11c is disposed the primary of a reactor-transformer 23a, whose secondary is disposed in the circuit to the positive filament of the lamp, comprising the relay coil 21b, ballast lamp 22, and conductors 20b and 13d. The secondary of the reactor-transformer is adapted to amplify the inductive kick generated by the opening of the primary winding of reactor transformer 23a when thermostatic switch contacts 17—18 open, and this amplified inductive kick

applied through the circuit to the positive filament of the lamp through conductors 20b and 13d will cause the lamp to fire and energize relay coil 21b, causing contacts 11c to reverse themselves from the position shown and to cut off the supply of preheating current through conductors 6d and 6e as well as short-circuiting the secondary winding of the reactor-transformer as soon as the lamp fires.

This arrangement provides a means for starting a lamp by impressing a higher voltage on it than can be obtained by breaking the circuit through a simple reactor. The use of such means has been found very desirable and efficient in starting certain long lamps as well as certain types of hard starting lamps. By use of the arrangement shown current flows through a reactor-transformer having its secondary disposed in such manner as to supplement the inductive kick obtained when the circuit through the preheating circuit is broken.

In the operation of this circuit, preheating current flows through the primary winding of the reactor-transformer 23a, the upper set of contacts 11c of the relay, the normally closed contacts 17-18 of the thermostatic switch 10', the heater element 9, and resistance 8b, to the filament 2 and thence to the negative side of the line. A circuit 20b is also established from the lower side of the primary winding of the reactor-transformer through its secondary winding, the relay coil 21b and the ballast lamp 22 to the short-circuited positive filament 3 of the lamp. The characteristic of the lamp being such that it will not fire without a heavy inductive kick being given to it, the negative filament 2 glows, but the lamp does not fire until the heater element 9 has heated the thermostatic switch for a sufficient length of time to cause its contacts 17-18 to open.

When these contacts open they cause an inductive kick or voltage surge through the primary winding of the reactor-transformer 23a, which is amplified by the secondary winding and the total value is sufficient to fire the lamp through the circuit from the secondary winding, the relay coil 21b, the ballast lamp 22 and the positive filament 3 of the lamp. When this takes place, the relay picks up and reverses its contacts, breaking the circuit to the thermostatic switch 10' and resistance 8b, and short-circuiting the secondary of the reactor-transformer. This arrangement prevails as long as the lamp continues to burn, allowing the thermostatic switch time to cool off and reclose its contacts 17-18 so as to be ready for another start.

If, when the lamp is operating, the line circuit is broken at any time, the relay reverses its contacts back to the normal position shown in Fig. 3, ready to initiate a restarting action as soon as the line circuit is again closed. By using the relay to short circuit the secondary winding of the reactor-transformer, as soon as the lamp has fired, the secondary winding can be made of a relatively large number of turns of small wire that will give a large supplementary boost to the inductive kick obtained by breaking the primary of the reactor-transformer, while at the same time keeping the secondary winding out of the circuit during the operation of the lamp, which is of advantage, as a low resistance and higher current carrying capacity are desired than would be obtained if the secondary winding were allowed to remain in the circuit with the lamp burning. This permits the reactor-transformer to be made smaller than would otherwise be the case.

It is to be understood that in the circuit organizations shown in Figs. 1, 3 and 4 the positive filament may be short-circuited or left open-circuited depending on the characteristics of the particular lamp used in the circuits.

Fig. 4 shows a circuit arrangement for use with a direct current supply somewhat similar to that of Fig. 3 and in which a simple reactor coil 23c is used in place of a reactor-transformer. In the operation of the circuit

shown in Fig. 4 current flows from the positive line terminal 14 through conductor 13f containing the reactor coil 23c through normally closed automatically reclosing relay switch 11e, conductor 6g, the normally closed contacts 17-18 of thermostatic switch 10', heater 9 of thermostatic switch 10', conductor 6h and resistance 8c to and through the lamp filament 2 and through conductor 4 to negative line terminal 5, thus establishing a preheating circuit to heat the filament 2. A branch circuit is also established from the low side of the reactor through relay coil 21d, ballast lamp 22 and conductor 13g, to the positive filament 3 of the fluorescent lamp.

When current is applied to the preheating circuit it heats up the heater element 9 and filament 2 and when the thermostatic switch 10' is heated sufficiently to cause the contacts 17-18 to open, these contacts on opening break the preheating circuit and cause the reactor 23c to give an inductive kick to start the lamp. This inductive kick is applied through the branch circuit containing the relay coil 21d and ballast lamp 22 to the positive filament 3 of the fluorescent lamp, whereby the fluorescent lamp is caused to fire. As soon as the lamp fires, the relay coil is energized and opens the switch 11e which prevents the preheating circuit from being re-established through the resistance 8c and negative filament 2 when the contacts 17-18 of the thermostatic switch reclose upon cooling. While contacts 17-18 are prevented at this time from closing the preheating circuit, they are in position to reclose the same and immediately restart the lamp if the line current is cut off to deenergize the relay coil and allow switch 11e to close. Then through re-application of line voltage the above described starting cycle will be repeated.

This circuit has the advantage over the ordinary type of circuit in which a thermostatic starter is used to maintain the running connections of the lamp in that in such a circuit, the thermostatic switch cannot immediately reclose upon removal of line voltage and hence there is a starting delay if the line circuit is opened and then almost immediately reclosed. During this time no current flows through the negative filament because the thermostatic switch contacts are open, and hence it is impossible to tell whether the circuit is completed or not, whereas, with the circuit arrangement shown in Fig. 4, contacts 17-18, under the same conditions, will immediately supply preheating current to the lamp when the line circuit is opened and then shortly reclosed. The subject matter of Fig. 4 is being claimed in applicant's co-pending application, Serial No. 144,345, filed February 15, 1950.

Preferably the circuit arrangements herein shown employ thermostatic starters of the quick-snap-switch type in which a pivoted switch member proper is connected by an insulated stem to a concavo-convex peripherally fixed bimetallic disk which is adapted to bow from one position to another in its opening and closing actions and which, according to the structural arrangement of its parts, may be either a normally open or a normally closed switch, as shown in the circuit arrangements herein disclosed.

A switch of this type is shown as used as a normally closed switch in some of the circuits herein disclosed.

As shown in Fig. 5, the switch has a fixed contact or pivoted switch member 18 which is connected by an insulated stem 18a to a bimetallic actuating disk of the character described arranged to be heated by the heater 9. Fig. 5 shows the switch member 18 in closed position and a coacting relay switch 11e is in its related closed position. When heated the disk 18b, which is normally bowed in one direction, is bowed in the opposite direction as shown in Fig. 6, whereby switch member 18 is opened. Fig. 6 shows the related position of the coacting relay switch 11e when the thermostatic switch contacts 17-18 are opened. The arrangement is in accordance with that shown in Fig. 4, but the thermostatic switch may be em-

ployed as a normally closed switch in other equivalent circuits or as a normally open switch by reversing the action of its parts in an obvious manner. It will be understood that after contacts 17-18 open, as shown in full lines in Fig. 6, and cause switch 11e to be opened to break the preheating circuit, contacts 17-18 upon cooling will return to closed position, as shown in dotted lines in Fig. 6, while switch 11e remains open as long as the lamp is operating.

All the circuits herein disclosed provide reliable, rugged and efficient starting and operating means for long and hard-starting fluorescent lamps which overcome the disadvantages of prior circuits using plain thermal and glow-switch types of starters and which have the additional advantages hereinbefore set forth. While the various arrangements disclosed for the purpose are preferred, it is, of course, to be understood that changes therein falling within the scope of the appended claims may be made without departing from the spirit of my invention.

Having thus described my invention, I claim:

1. In combination, a gaseous electric discharge device having two electrodes, at least one of which is constructed to receive preheating current, a supply circuit, a relay comprising a double-throw switch having normally closed and normally open contacts and an operating coil, a transformer having primary and secondary windings, means including said primary and secondary windings and said operating coil in series connection for connecting said electrodes to said supply circuit, a delay device having an operating circuit and normally closed contacts, an electrode preheating circuit capable of producing firing temperature electrode heating, said circuit extending from one side of a voltage source to the opposite side of said source and including in series connection said electrode to be preheated, said primary winding, said normally closed relay switch contacts, said delay device operating circuit and said delay device contacts, the opening of said delay device contacts causing the discharge device to fire by an inductive voltage surge including the voltage produced by said secondary winding, the operating current of the discharge device causing operation of said relay thereby closing said normally open contacts so as to short circuit the transformer secondary, and opening said normally closed contacts so as to interrupt the preheating circuit and maintain said circuit open during the operation of the discharge device.

2. In combination, a gaseous electric discharge device having two electrodes, at least one of which is constructed to receive preheating current, a supply circuit, a relay comprising a double-throw switch having normally closed and normally open contacts and an operating coil, a transformer having primary and secondary windings, means including said primary and secondary windings, said operating coil and a current controlling device in series connection for connecting said electrodes to said supply circuit, a delay device having an operating circuit and normally closed contacts, an electrode preheating circuit capable of producing firing temperature electrode heating, said circuit extending from one side of a voltage source to the opposite side of said source and including in series connection said electrode to be preheated, said primary winding, said normally closed relay switch contacts, a current limiting device, said delay device operating circuit and said delay device contacts, the opening of said delay device contacts causing the discharge device to fire by an inductive voltage surge including the voltage produced by said secondary winding, the operating current of the discharge device causing operation of said relay thereby closing said normally open contacts so as to short circuit the transformer secondary and thus connect one of said electrodes to the supply circuit through said primary winding, said relay operating coil and said current controlling device, and the operation of said relay also opening said normally closed contacts so as to interrupt the preheating circuit and

5 maintain said circuit open during the operation of the discharge device.

3. In combination, a gaseous electric discharge device having two electrodes, one of which is constructed to receive preheating current, a supply circuit, a relay comprising a double-throw switch having normally closed and normally open contacts, and an operating coil, a transformer having primary and secondary windings, means including said primary and secondary windings and said operating coil in series connection for connecting the unheated electrode to said supply circuit, a delay device having an operating circuit and normally closed contacts, an electrode preheating circuit capable of producing firing temperature electrode heating, said circuit extending from one side of said supply circuit to one terminal of the electrode to be preheated, said preheating circuit continuing from the opposite terminal of said electrode and including in series connection said delay device operating circuit, said delay device contacts, said normally closed relay switch contacts and said primary winding, the opening of said delay device contacts causing the discharge device to fire by an inductive voltage surge including the voltage produced by said secondary winding, the operating current of the discharge device causing operation of said relay thereby closing said normally open contacts so as to short circuit the transformer secondary, and opening said normally closed contacts so as to interrupt the preheating circuit and maintain said circuit open during the operation of the discharge device.

4. In combination, a gaseous electric discharge device having two electrodes, one of which is constructed to receive preheating current, a supply circuit, a relay comprising a double-throw switch having normally closed and normally open contacts and an operating coil, a transformer having primary and secondary windings, means including said primary and secondary windings and said operating coil and a current controlling device in series connection for connecting the unheated electrode to said supply circuit, a delay device having an operating circuit and normally closed contacts, an electrode preheating circuit capable of producing firing temperature electrode heating, said circuit extending from one side of said supply circuit to one terminal of the electrode to be preheated, said preheating circuit continuing from the opposite terminal of said electrode and including in series connection said delay device operating circuit, said delay device contacts, a current limiting device, said normally closed relay switch contacts, the opening of said delay device contacts causing the discharge device to fire by an inductive voltage surge including the voltage produced by said secondary winding, the operating current of the discharge device causing operation of said relay thereby closing said normally open contacts so as to short circuit the transformer secondary and thus connect the unheated electrode to the supply circuit through said primary winding, said relay operating coil and said current controlling device, and the operation of said relay also opening said normally closed contacts so as to interrupt the preheating circuit and maintain said circuit open during the operation of the discharge device.
